UNITED STATES PATENT OFFICE.

FRANK J. TONE, OF NIAGARA FALLS, NEW YORK.

ELECTRICAL CONDUCTOR AND JOINT THEREFOR.

No. 836,155.

Specification of Letters Patent.

Patented Nov. 20, 1906

Application filed November 11, 1905. Serial No. 286,796.

To all whom it may concern:

Be it known that I, FRANK J. TONE, of Niagara Falls, Niagara county, New York, have invented a new and useful Improvement 5 in Electrical Conductors and Joints Therefor, of which the following is a full, clear, and exact description, reference being had to the accompanying drawings, forming part of this specification, in which—

10 Figure 1 is a top plan view, partly in section and with the circuit connections omitted, of a conductor or electrode constructed in accordance with my invention. Fig. 2 is a vertical section on the line II II of Fig. 1 with the electrical connections shown. Fig. 15 3 is a plan view showing a modification; and Fig. 4 is a side elevation, partly in vertical section, of the form shown in Fig. 3.

The invention relates to electric conductors, and particularly to electrodes which are used in electric furnaces for the purpose of conducting a current to the zone of high temperature and reaction within the furnace. These features usually consist of one or 20 more carbon rods or blocks, one end of which is in proximity to the zone of reaction, and the other end of which makes contact outside the furnace with a metal conductor connected with a source of electric energy.

25 One feature of the invention has particular reference to the method of making contact between the carbon and its metal conductor or holder. Ordinarily these parts have been joined by simply bringing their surfaces into contact, it being necessary to machine or otherwise fit such surfaces very accurately in order to avoid small contact areas, which becoming overheated destroy the surface of the metal and shorten the life 30 of the electrode or terminal. The invention is designed to obviate this machining of the contact-surfaces by interposing between them a layer of graphite, preferably that form of graphite which is produced in electric furnaces. This form of graphite has 35 peculiar properties, among them great density and a capability of being readily compressed and molded, which make it extremely suitable for this purpose. In fact, this capability is present to such a degree that the material may in a sense be termed "plastic,"

40 which is not true of natural graphite. If portions of natural and electrically-produced graphite be subjected to equal pressure, the electrically-produced graphite is found to be

a fine-grained mass of good strength and capable of being cut and machined. The compressed mass of natural graphite, on the contrary, cannot be cleanly cut or machined, and its cohesive and moldable properties are 45 so inferior that a binder must be added. The peculiar properties of the electrically-produced material I attribute to its fine state of subdivision due to the complete breaking up of each molecule of the carbide apparently 50 without fusion.

In practicing my invention the interposed graphite layer is by suitable means compressed between the contact-surfaces into a dense layer of high conductivity and having 55 most intimate contact with the adjacent surfaces regardless of their inequalities. This feature of my invention is also applicable generally to joints in electrical conductors where it is essential to make a perfect 60 electrical connection of high conductivity.

Another feature of my invention consists in providing the electrode or conductor with a water-jacket having means for providing a circulation of water or other cooling medium 65 therethrough. This not only serves the purpose of keeping the metal-holder, which becomes highly heated by reason of the heat transmitted from the zone of reaction within the furnace below the fusion-point, but also 70 very considerably reduces the corrosion and oxidation of the metal, which at high temperatures is ordinarily very rapid. It also serves to keep the metal at a normal temperature, where its electrical conductivity is 75 highest.

Another feature of the invention consists in providing the carbon electrodes or conductors with means for preventing the oxidation of those portions of them which are exposed 80 to the air and become overheated. This I do by surrounding them with a layer of cemented refractory material, for which purpose various silicocarbids, such as crystalline and amorphous carborundum and siloxicon, are 85 found to be well adapted. This refractory material is mixed with a suitable binder, such as cement or silicate of soda, and the mixture is brought to the consistency of a 90 stiff mortar. It is then molded into a jacket 95 which conforms to the exterior shape of the carbons which compose the electrode. In some cases I have also found it useful to place cooling means within the mass of refractory material composing this jacket to 100

105 110

preserve it from the effect of excessive heat and to supplement the cooling of the electrode by the water-cooled holder above described.

In the accompanying drawings, to which reference is made for a more complete understanding of my invention, Fig. 1 shows two carbon bars or blocks 2 2 assembled to form an electrode. 3 3 are metal holding and clamping bars, having suitable projections 4, to which are connected the terminals of the supply-conductors 5. The clamping-bars 3 are connected and clamped firmly against the carbons 2 by means of threaded bolts or nipples 6. Before assembling these parts a layer of graphite (indicated at 7) is placed between the clamping-bars and the carbons at their surfaces of contact, and sufficient pressure is then exerted to compress this graphite layer, which, as will be readily seen, completely adapts itself to all irregularity of the adjacent surfaces. The clamping-bars 3 and the nipples 6 are cored out to provide channels 8 for the circulation of cooling water or other cooling medium which enters and discharges through the circulating-pipes 9.

10 is a refractory coating or jacket of the character above described and which is employed for the purpose of protecting the exposed portions of the carbons from oxidation. This coating or jacket is provided with circulating-ducts 11, molded therein for the passage through the jacket of a cooling medium which may be supplied from any suitable source, as by connecting said ducts with the circulating-passage 8' in the clamping-bars 3.

The construction shown in Figs. 3 and 4 illustrate the invention applied to an electrode of circular form, the construction and arrangement of the bars except for the change in shape to suit the circular form of the carbon being the same as in Figs. 1 and 2 and above described.

I do not limit myself to the use of any particular form of carbon for the conductors or electrodes, as these may be either of amorphous, graphitized carbon, or other forms.

The advantages of my invention result from the perfect electrical contact which is secured between the carbon or carbons and the holders, the effective manner in which the exposed holders or clamps are protected from excessive heat, and the means by which the exposed portions of the carbon are jackeded to prevent oxidation.

Various changes may be made in the form, shape, and character of the conductors or electrodes in the holders or connectors therefor and the particular means employed for clamping the holders and in other details without departing from the spirit and the scope of my invention, since

What I claim is—

1. A joint for electric conductors having between the surfaces to be connected a layer

of compressed electrically-produced graphite; substantially as described.

2. The combination with an electrode, of a metal connecting member or holder and a layer of electrically-produced graphite between the contacting surfaces of the electrode and the connector or holder; substantially as described.

3. A joint for electric conductors having a layer of artificial electrically-produced graphite between the contact-surfaces to be connected, and means for compressing the graphite layer; substantially as described.

4. An electrode comprising one or more carbon rods, a metal connector or holder for said rods, a layer of graphite between the contact-surfaces of the carbons and the connector or holder, and means for joining the carbons and the connector or holder and at the same time, compressing the graphite layer between them; substantially as described.

5. An electrode comprising one or more carbon rods, a water-jacketed metal connector or holder for said rods, a layer of graphite between the contact-surfaces of the carbons and the connector or holder, and clamping means for securing the carbons and connector or holder and compressing the graphite layer between them; substantially as described.

6. An electrode comprising one or more carbon rods, clamping members having circulating-passages therein, and connecting means for said clamping members also having circulating-passages connecting the first-named passages; substantially as described.

7. An electrode comprising one or more carbon rods, a two-part clamp or holder for the same, having circulating-passages therein, a layer of graphite between the contact-surfaces of the carbon rods and the holder, and connecting means for the parts of said holder also having circulating-passages therein; substantially as described.

8. An electrode having one or more carbons, and a body of cemented refractory material surrounding the carbons and protecting them from oxidation, said body being provided with ducts for the circulation of cooling medium; substantially as described.

9. An electrode comprising one or more carbons, a metal connector, a layer of graphite between the contact-surfaces of the carbons and the connector, means for joining the carbons and the connector and compressing the graphite layer between them, and a body of cemented silicocarbide around the carbons, and protecting them from oxidation; substantially as described.

10. An electrode comprising one or more carbons, a water-jacketed metal connector, a layer of electrically-produced graphite between the contact surfaces of the carbons and the connector, means for joining the

carbons and connector and compressing the graphite layer between them, and a body of cemented silicocarbide around the carbons, and protecting them from oxidation; substantially as described. 15

11. An electrode comprising one or more carbons, a water-jacketed metal connector, a layer of graphite between the contact-surfaces of the carbons and the connector, 10 means for joining the carbons and the connector and compressing the graphite layer be-

tween them, and a body of cemented refractory material around the carbons, said body being provided with ducts for the circulation of a cooling medium; substantially as described. 15

In testimony whereof I have hereunto set my hand.

FRANK J. TONE.
